UNITED STATES PATENT OFFICE.

JOSEPH D. SHEEHAN, OF BROOKLYN, NEW YORK.

GAS-BURNER ATTACHMENT.

No. 851,564.

Specification of Letters Patent.

Patented April 23, 1907.

Application filed August 21, 1905. Serial No. 275,190.

To all whom it may concern:

Be it known that I, JOSEPH D. SHEEHAN, a citizen of the United States, residing at 5413 Fourth avenue, Brooklyn, in the county of 5 Kings and State of New York, have invented new and useful Improvements in Gas-Burner Attachments, of which the following is a specification.

This invention relates to cut off attachments for gas burners, designed particularly for use with gas burners carrying incandescent mantles.

The objects of the invention are to improve and simplify the construction of such devices; furthermore, to increase their efficiency in operation, and to decrease the expense attending their manufacture.

With the foregoing and other objects in view which will appear as the description 20 proceeds,—the invention resides in the combination and arrangement of parts, and in the details of construction hereinafter described and claimed as a practical embodiment thereof.

25 In the accompanying drawing forming part of this specification,—Figure 1 is a vertical sectional view, partly in elevation illustrating the invention, the valve being shown in raised position, Fig. 2 is a similar view, 30 omitting the mantle and gas pipe, the valve being shown in closed position, Fig. 3 is an enlarged detailed sectional view of the air cylinder.

In the construction illustrated in the drawings, the gas supply pipe 30, having the usual form of cock or cut-off 31 is provided with an upward extension 32 having a plug section 33 in the upper end thereof. The plug section 33 is formed with a small passage 34 which 40 terminates at its upper end in a cone shaped valve seat 35. Surrounding the upward extension 32 is a burner section 36 having air inlet holes or openings 37 which are disposed below the upper end of the plug section 33.

45 Mounted in any suitable manner upon the upper end of the burner section 36 is a collar 38 to which is secured in any suitable manner a large burner section 39 on which the incandescent mantle 40 is supported in any convenient and well known manner. Supported within the burner section 39 by means of braces 41, is a cylinder 42 having an open lower end. Mounted within the cylinder 42 is a piston 43 through which extends a piston 50 rod 44 having on the lower end thereof a cone shaped valve 45 adapted to fit into and close

the valve seat 35. The piston rod 44 is provided with a laterally extending arm 46 which is adapted to be engaged by a cam member 47 having a handle portion 48 projecting outward through the burner section 36, and being pivotally mounted as indicated at 49. Formed in the upper end of the cylinder 42 is a cone shaped valve seat into which is fitted a cone shaped valve 50 having a valve stem 51 extending through a bracket or guide-arm 52 mounted upon the cylinder 42. Extending through the valve 50 and stem 51 is a small air passage 53.

The piston rod 44, above the cylinder 42 is formed of brass or copper and is bent at its upper end as indicated at 54. Secured to the upper end of the piston rod 44 is a strip 55 of steel or other metal having a lesser degree of expansibility when subjected to the action of heat, than the metal of which the upper end of the piston rod is formed. The strip 55, therefore, in combination with the upper end of the piston rod serves to produce a thermostat which is adapted to be flexed 80 by the action of heat, from the straight position shown in Fig. 2, to the curved position shown in Fig. 1.

Constructed as described, the device is operated in the following manner:—The cut-off 31 is opened, and the cam member 47 is raised by hand, so as to elevate the piston rod 44 from the position illustrated in Fig. 2 to the position illustrated in Fig. 1. As the piston 43 moves upward in the cylinder 42, the valve 50 is raised so as to permit the escape of air from the upper end of the cylinder. As soon as the piston has reached the limit of its upward movement, the valve 50 drops back into position to close the upper end of the cylinder. As the piston 43 attempts to descend, air is forced to enter through the small passage 53, for which reason the descent of the piston 43 and consequently the valve 45 is retarded for a sufficient length of time to permit a quantity of gas to pass through the plug section 33 and enter the mantle 40, where the same is ignited by a match held in the vicinity thereof in the usual manner. As soon as the mantle 105 is properly ignited, the action of the heat causes the thermostat at the upper end of the piston rod 44 to flex or bend in such manner as to engage a brace 57 which is arranged across the upper end of the burner section 39. 110 As soon as the thermostat engages the brace 57, the valve 45 is held in elevated position

as long as the mantle remains properly ignited. In the event that the gas supply should fail, the thermostat would cool off and assume the straight position shown in Fig. 2, so that the piston rod 44 would descend gradually by gravity and cause the valve 45 to close the valve seat 35 and prevent the escape of gas.

The improved device of this invention is 10 strong, simple, durable and inexpensive in construction as well as thoroughly efficient in operation.

Changes in the precise embodiment of invention illustrated and described may be 15 made within the scope of the following claims without departing from the spirit of the invention or sacrificing any of its advantages.

Having thus described the invention what is claimed as new is:—

- 20 1. The combination of a gas supply pipe, a plug section therein having a valve seat, a small burner section surrounding the plug section and having air inlets disposed below the valve seat, a large burner section connected with the small burner section and having braces therein, an air cylinder supported by the braces and having the lower end thereof open, a one-way valve in the upper end of the cylinder, having a small passage there-
25 through, a piston located in the cylinder, a piston rod extending through the piston and cylinder, a valve on the lower end of the piston rod, a thermostat on the upper end of the piston rod, and a brace extending across the large burner section and being adapted to

be engaged by the thermostat, substantially as described.

2. The combination with a gas supply pipe formed with a valve seat, a burner section arranged above the valve, a thermostat 40 movable within the section and carrying a valve to coöperate with said seat, means for manually operating the thermostat to unseat the valve, and means to retard the gravitation of said valve to closed position when 45 released from the manual operating means, said retarding means including an air cylinder having a valved inlet at the upper end, and a piston disposed within said cylinder and connected to the thermostat.

3. The combination with a gas supply pipe having a valve seat, a burner section above the valve seat, a thermostat movably supported within the burner section and carrying a valve to engage said seat, means for 55 manually operating the thermostat to unseat the valve, means for automatically retarding movement of the thermostat when released from the manual operating means, a stop supported within the burner above the 60 upper end of the thermostat in normal position, and a projection carried by the thermostat to engage said stop in the movement of the thermostat under the influence of heat.

In testimony whereof, I have affixed my 65 signature in presence of two witnesses.

JOSEPH D. SHEEHAN.
